UNITED STATES PATENT OFFICE

123,181

DESIGN FOR A CLOCK OR SIMILAR ARTICLE

William Stanley Roth, New York, N. Y., assignor of one-half to Lawrence E. Arzt, New York, N. Y.

Application August 1, 1940, Serial No. 94,128

Term of patent 3½ years

To all whom it may concern:

Be it known that I, William Stanley Roth, a citizen of the United States, residing in the Borough of Manhattan, city of New York, county of New York, and State of New York, have invented a new, original, and ornamental Design for a Clock or Similar Article, of which the following is a specification, reference being had to the accompanying drawing, forming part thereof.

I claim:

The ornamental design for a clock or similar article, as shown.

WILLIAM STANLEY ROTH,
